UNITED STATES PATENT OFFICE.

WILLIAM H. VOSS, OF DAVENPORT, IOWA.

WASHING-MACHINE GEARING.

1,230,542.

Specification of Letters Patent. Patented June 19, 1917.

Application filed November 10, 1915. Serial No. 60,630.

To all whom it may concern:

Be it known that I, WILLIAM H. Voss, a citizen of the United States, residing at Davenport, in the county of Scott and State of Iowa, have invented certain new and useful Improvements in Washing-Machine Gearing, of which the following is the specification.

This invention relates to gearing, and particularly to gearing applicable to washing machines and the like.

It is an object of the invention to provide a simple, and economically constructed washing machine and to eliminate therefrom all possible gearing connections while retaining all of the functions which a combined washer and wringer mechanism should be able to perform.

It is another object of the invention to provide a washing machine having a novel form of drive for the dolly and a construction in which most of the operating mechanism therefor is down under the platform which supports the tub, and out of the way.

It is a further object of the invention to provide a machine of the class described in which the lid may be raised without breaking the driving connection for the dolly so that it is not necessary to mesh and unmash the gears when the lid is raised. This is an important feature of the invention and it is believed to be broadly new.

Further objects and advantages of the invention will appear as the description to follow proceeds.

In the drawings:

Figure 1 is a perspective view of the complete machine.

Fig. 2 is a plan view thereof.

Fig. 3 is a detail perspective view of a portion of the operating mechanism.

Fig. 4 is a detail perspective view showing the operating handle.

Fig. 5 is a detailed sectional view of the driving mechanism.

Fig. 6 is a detailed sectional view of a portion of the operating mechanism for the rocker shaft.

Fig. 7 is a detail sectional plan view of the clutch construction.

Fig. 8 is a detail elevation of the clutch.

Fig. 9 is a sectional elevation of the entire machine.

1 represents a platform provided with a wooden top, and channeled iron legs 2 suit-

ably braced. A supplementary platform is provided comprising angle irons 3 and 3' firmly bolted to the legs 2. Upon one of the angle irons 3 is mounted a bearing 4 aligned with which is a bearing 5, the bearings 4 and 5 supporting the main drive shaft 6 of the machine, which is provided with belt wheel 7. The bearing 5 is supported upon the upraised inner end of a shelf 8 which at one end is bolted to one of the angle irons 3 and at its inner end is provided with an upraised portion 9 having a lug 10 bolted to one of the angle irons 3'. The shelf 8 is provided with a vertical bearing 12 in which is mounted the vertical shaft 11 which at its upper end is connected to drive the wringer in a fashion hereinafter to be described. Supported upon the bearing 12 and secured to the shaft 11 is a beveled crown gear 13 in mesh with a pinion 14 upon the drive shaft 6. Adjacent its lower end the shaft 11 is provided with a transverse pin 15 (see Figs. 7 and 8) below which is sleeved upon the shaft 11 a clutch 16 having upper cam faces 17 terminating in a slot 18. The clutch 16 is provided with a peripheral groove 19 in which is engaged the bent link 20 joining the ends 21 of a fork 22 upon the end of an arm 23 which is pivoted in the frame upon a special depending bracket 24 and terminates at its other end in a handle 25 engageable in either of two notches 27 in the strip 28 secured to the support. By this means the clutch 16 may be raised or lowered to engage or disengage the pin 15 with the slot 18. Upon the lower end of the clutch 16 is a crank arm 30 with which is pivotally connected the bent link 31 which at its other end is pivotally connected with the crank arm 32 mounted upon the lower end of a shaft 33 mounted in a bearing 34 secured to a bracket 35 mounted upon one of the angle irons 3'. Shaft 33 at its upper end is mounted in a bearing 36 extended into a curved flange 37 secured to the tub and the shaft 33 is provided at its upper end with a crank arm 38 which is pivotally connected to a curved link 39 in turn connected at its forward end to a rack 40.

In contradistinction to the general practice and as an important feature of my invention I mount the lid 41 of the tub with its hinge line substantially centrally concentric with the rack bar 40. The entire cover for the top of the tub is divided into two

parts, the stationary segment 42 is permanently secured to the tub and carrying a plate 43 having at either end curved brackets 44 which are extended downwardly and bolted to the tub, and have upwardly extending portions in which is mounted the rod 45 upon which the rack 40 is sleeved. To the movable lid portion 47 of the tub is attached a plate 48 having at its ends bearings 49 for the ends of the rod 45. The rod 45 is held against longitudinal movement by cotter pins 50 at its ends. The plate 48 is provided with apertures for the journal 51 of an idler gear, and a dolly shaft 52. Secured to the plate 48 by bolts passing through at least a layer of the lid is a casting 53 having a corresponding bearing having an enlarged portion to cover the idler gear shown, and a curved flange 54 to act as a guard for the rack 40, and a dome 55 to house the upper end of the dolly shaft 52. The dolly shaft is driven by a pinion 56 in mesh with the idler 57, both the dolly shaft and idler 57 being journaled in the plate 48 and casing 53, as above described.

To drive the machine I provide an electric motor 57' mounted dependingly supported from one of the channel bars 3, and driving the belt pulley 7 on the drive shaft 6. A clamp, represented generally by the reference numeral 59 holds the lid closed. The bent lugs 60 are bolted to the shield 54, the other end serving to support the cover when in raised position. When the cover is to be raised the wringer may be swung outwardly so as not to interfere.

In operation it will be seen that the belt pulley 7 drives the shaft 6 which drives the bevel crown gear 13 and, therefore, the vertical shaft 11 which drives the wringer and is connected thereto by a clutch so that the wringer can be operated or not as desired. The specific construction of the wringer and this operating mechanism forms no part of the present invention. By operating the clutch 16 through the handle 23 the shaft 33 may be rocked or not, as desired. When this shaft is in operation the cylindrical rack 40 is reciprocated driving the idler 57 which through pinion 56 operates the dolly. Because the hinge line of the cover is concentric with the rack 40 and this rack is cylindrical in form the cover may be raised or lowered without disturbing the meshing engagement of the idler 57 with the rack 40.

Having now described my invention I claim:

1. In apparatus of the class described, a support, a hinged member on the support, an oscillatory gear on the hinged member, a rack bar for operating the gear, including means for maintaining the engagement of the rack bar with the gear when the hinged member is raised on its hinges.

65 2. In apparatus of the class described, a

support, a hinged member on the support, an oscillatory gear on the hinged member, a rack bar for operating the gear, including means for maintaining the engagement of the rack bar with the gear when the hinged member is raised on its hinges, and an oscillatory shaft operated by said pinion. 70

3. In apparatus of the class described, a support, a hinged member thereon, an oscillatory gear on the hinged member, a reciprocable rack bar engaging said gear, said rack bar being in the hinge line of said hinged member. 75

4. In apparatus of the class described, a support, a hinged member thereon, an oscillatory shaft on said hinged member, a pinion on said shaft, a rack bar engaging said pinion and lying in the hinge line of said hinged member, a semi-cylindrical rack on said rack bar whereby said rack will remain 80 in engagement with said pinion when the hinged member is swung on its hinges. 85

5. In apparatus of the class described, a drive shaft, a vertical shaft driven therefrom, a second vertical shaft, connections between 90 said vertical shafts to oscillate the latter from the former, a hinged member, an oscillatory shaft in said hinged member, and a link connection between said second vertical shaft and said oscillatory shaft to oscillate the latter, including a rack bar. 95

6. In apparatus of the class described, a drive shaft, a vertical shaft driven therefrom, a second vertical shaft, connections between 100 said vertical shafts to oscillate the latter from the former, a hinged member, an oscillatory shaft on said hinged member and a link connection between said second vertical shaft and said oscillatory shaft to oscillate the latter, including a rack bar, and means 105 to interrupt the driving connections between the two vertical shafts.

7. In apparatus of the class described, a support, a drive shaft under the support, a vertical shaft operatively connected with 110 and oscillated from said drive shaft, a crank on said vertical shaft, a hinged member, an oscillatory shaft in said hinged member, a rack connected with said crank and operatively connected with said oscillatory shaft. 115

8. In apparatus of the class described, a support, a vertical rocking shaft thereon, a hinged member on the support, a crank on the vertical shaft, an oscillatory shaft in said hinged member having a pinion thereon, a rack operatively connecting said crank and said pinion, said rack lying adjacent the hinge line of said hinged member. 120

9. In apparatus of the class described, a support, a vertical shaft thereon adapted to 125 rotate in vertical bearings, means for oscillating said vertical shaft, a hinged member on said support, an oscillatory shaft on said hinged member, a reciprocal bar connecting said vertical shaft to said oscillatory shaft 130

and lying adjacent and parallel to the hinge line of said hinged member.

10. In apparatus of the class described, a support, a rotary shaft thereon, a vertical shaft, connections between said rotary shaft and said vertical shaft for oscillating the latter about its own axis from the former, a hinged member on the support, an oscillatory shaft in said hinged member, a link 10 connection between said vertical and said oscillatory shafts.

11. In apparatus of the class described, a support, a rotary shaft thereon, a vertical shaft mounted for rotation in vertical bearings, connections between said rotary shaft and said vertical shaft for oscillating the latter from the former, a hinged member on the support, an oscillatory shaft in said hinged member, a link connection between 15 said vertical and said oscillatory shafts, said link connection lying adjacent and

parallel to the hinge line of said hinged member.

12. In apparatus of the class described, a support, a rotary shaft thereon, a vertical 25 shaft mounted for rotation in vertical bearings, connections between said rotary and said vertical shafts for oscillating the latter from the former, a hinged member on the support, an oscillatory gear on said hinged 30 member, a link connection between said vertical shaft and said gear, and an oscillatory shaft in said hinged member driven from said oscillatory gear.

In witness whereof, I hereunto subscribe 35 my name to this specification in the presence of two witnesses.
